CLAIM

The ornamental design of a bread carving knife, as shown and described.

DESCRIPTION

FIG. 1 is a front perspective view of a bread carving knife, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective view thereof, shown in environmental use.

The broken lines in the drawings depict portions of the bread carving knife; that form no part of the claimed design.

The broken lines that form the attachment in FIG. 8 are for illustrating environment only and form no part of the claimed design.

1 Claim, 7 Drawing Sheets
